(57) **CLAIM**

The ornamental design for a spill kit dispenser, as shown and described.

DESCRIPTION

FIG. 1 is an isometric view of a spill kit dispenser showing my new design;

FIG. 2 is an isometric view thereof shown in an open position;

FIG. 3 is a front view of FIG. 1;

FIG. 4 is a back view of FIG. 1;

FIG. 5 is a right side view of FIG. 1;

FIG. 6 is a left side view of FIG. 1;

FIG. 7 is a top view of FIG. 1; and,

FIG. 8 is a bottom view of FIG. 1.

The broken lines shown represent unclaimed subject matter and form no part of the claimed design.

1 Claim, 6 Drawing Sheets(56)
